UNITED STATES PATENT OFFICE

ALBERT EDWARD HODGSON AND NORMAN CLARKE JONES, OF LONDON, ENGLAND

APPARATUS FOR GENERATING OIL GAS

Application filed March 16, 1927, Serial No. 175,878, and in Great Britain May 31, 1926.

This invention relates to apparatus for the generation from heavy oils of oil gas that can be used as the fuel supply for internal combustion engines of automobiles, tractors, agricultural sets, quarrying sets, small marine craft, stationary plants and the like, or for use for heating purposes for furnaces and the like.

The object of the invention is to design such apparatus that will work on the suction gas principle, simplify the construction so that worn parts can be easily replaced and which will be readily portable, to provide means whereby the gas emitted from the generator shall be cooled to some extent by the incoming air which is used for the gas generation or for supporting the combustion of the fuel, the apparatus comprising a generator into which the oil fuel is regulatably fed and is vaporized on inclined perforated baffle plates disposed within the generator.

In the annexed drawings is diagrammatically illustrated apparatus constructed in accordance with the present invention in which:

Figure 1 is an elevation of the complete apparatus or assembled parts, the apparatus for cleansing and mixing the gas forming the subject matter of a co-pending application for patent Serial No. 249,982, dated January 27th, 1928.

Figures 2 and 3 are sectional elevation and plan views respectively of the generator.

Referring now to the drawings, in which similar reference characters relate to like parts in all the figures thereof, the entire assembled apparatus is illustrated in Figure 1 in which G represents the oil gas generator, S the scrubber and M the mixing chamber and filter the details of the generator being more particularly hereinafter described.

The oil gas generator G is illustrated in Figures 2 and 3 and comprises a steel receptacle a that is open at the top and fitted internally at its bottom with an angular flange b that forms an annular chamber c. This annular chamber c is provided with a number of holes c' that serve as air passages for the admission of air as will be hereinafter described. Beneath these holes c' and resting

on the bottom of the gas generating chamber a is a lining d of suitable refractory material.

Resting upon the top of the chamber c is the refractory lining e, the top of the flange b is preferably wider than the thickness of the lining e so that a space is left and upon this space or ledge formed thereby rests two or more superimposed preferably inclined distributing plates f made of cast iron, steel or of suitable refractory material provided with suitable holes that constitute baffles or distributing plates within the gas generating chamber for the fuel.

The steel casing terminates in a flange g situated at some distance above the top of the lining and in the space between the top of the lining and the flange g is provided an oil heating coil h hereinafter referred to, whilst on the side of the casing a is or are provided a branch or branches i for the gas exit from the generator G.

The annular chamber c at the bottom of the generator is provided with two air admission tubes j one of which passes through the gas exit tube k, these air admission tubes j are open to the atmosphere and are provided with any suitable valve m for regulating the admission of air which is drawn into the gas generating chamber through the tubes j by the suction of the engine that is connected with the conduit i, but is not shown in the drawing.

On the top flange of the casing or drum a is fixed a cover plate n provided with a readily movable lid o and through the cover plate n passes the oil inlet pipe p which is connected to the coil h situated between the cover plate n and the top of the lining e so that the oil passing from the coil h is heated by the exit gases. The heating coil h terminates in a depending pipe or jet q through which the oil passes into the gas generating chamber. The supply pipe having a vertical extension r that also passes through the cover plate n and serves for the purpose of cleaning the jet q. The oil inlet pipe is connected with a needle valve s which is connected to the throttle of the engine the connection being so regulated that when the throttle is opened the needle valve allows the admission of the

quantity of oil necessary for the engine requirements.

The oil inlet pipe p is also provided with the valve t which can be set at a fixed feed, this valve being normally used for stationary engine and furnace operation. The needle valve s and fixed feed valve t are connected to a suitable oil storage tank fixed so that oil will flow thereto by gravity by way of pipes u and u' .

The casing of the generator is provided with a door v which affords communication with the interior thereof for cleaning and inspection purposes. Below this door there is fixed in the gas generating chamber an oil jet or burner w provided with the needle valve 2 which can be operated by hand. This burner w is used for starting up purposes. Surrounding the needle valve 2 is an air pipe 3 provided with a T piece 4, one branch 4^a of which is open to the atmosphere and provided with any suitable means for regulating the admission of air thereto. The other branch of the T piece 4 is connected to a small supply tank 5 fitted with a small hand pressure pump 6 while a suitable regulating valve 7 is provided in the connecting pipe 4^b. This tank 5 may for convenience be fixed on the cover n of the generator G.

The oil jet w is connected by the pipe 8^a with a small supply tank 8 which may be fixed upon the cover n of the generator or may be a compartment of the main oil supply tank. This tank or compartment is fitted with a small hand pressure pump 9.

The gas exit i from the generator G is connected to a scrubber or separating device S for purifying purposes, the apparatus forming the subject matter of our copending application for patent aforesaid.

The method of operation is as follows:—

Referring particularly to Figure 1 of the drawings the door v and the lid o are removed from the generator G and the needle valve 2 opened so that a thin jet of oil passes by way of the pipe 8^a into the gas generating chamber through the burner w from the container 8. The jet of oil is ignited and a stream of air compressed in the tank 5 is allowed to pass by way of pipe 4^b into the tube surrounding the burner w . This stream of air is controlled by valve 7. When the generator becomes heated the door v and lid o are closed, the air regulator 28 opened and the throttle 31 closed. The regulating valves m on the air admission tubes j are now set at a suitable opening and a regulated quantity of oil allowed to enter the generator G by means of the jet q the oil feed regulator t being set for a fixed feed. The needle valve 2 and the air valve 7 are now closed. The fan 17 is then rotated until it is found that the gas issuing from valve 28 will ignite. The throttle 31 to which is connected the needle oil control valve s is now opened to the extent necessary for

starting purposes and the fixed oil feed t is closed, the gas being conveyed to the filter M by the pipe 27. The engine is then started in the usual way being controlled by the throttle 31 and air regulator 28. When starting up with petrol the procedure is as above described the engine being however started up immediately before opening throttle 31; the engine will of course work on the two fuels i. e. oil gas and petrol, the petrol being slowly shut off as the oil gas generation becomes steady and continuous.

To facilitate the comprehension of the above explanation of working, the pipe connections between the engine induction and the filter M are shown in plan above the filter M in Figure 1 and may be summarized as follows:—25 the exit from the filter M is connected directly to the throttle 31 to which is fixed the three-way piece 32 one branch of which is connected to the engine induction 33, the second 34 to a control throttle and carburettor and the third to the throttle 31 as aforesaid.

What we claim is:—

An apparatus for generating oil gas; comprising an oil gas generating chamber having an outer steel casing and an inner refractory lining, inclined perforated baffle plates attached to the refractory lining within the gasifying chamber, an oil inlet coil within the upper portion of the gasifying chamber above the refractory lining, whereby the oil is preheated by the generated gas, an annular air admission chamber at the base of the gas generating chamber, an air inlet pipe leading to the air admission chamber, and an oil gas outlet pipe surrounding a portion of the air inlet pipe, whereby the air is preheated by the outlet oil gas.

In testimony whereof we affix our signatures.

ALBERT EDWARD HODGSON.
NORMAN CLARKE JONES.
